DESIGN FOR A MIRROR CLOCK COMBINATION

Application filed May 29, 1931. Serial No. 40,033. Term of patent 7 years.

To all whom it may concern:

Be it known that I, STEPHEN C. COOK, a citizen of the United States, and a resident of the borough of Brooklyn, county of Kings, city and State of New York, have invented a new, original, and ornamental Design for Mirror Clock Combination, of which the following is a specification, reference being had to the accompanying drawings, forming a part hereof.

Referring to the annexed sheet of drawings:

Figure 1 is a plan view of a mirror clock combination showing my new design.

Figure 2 is an end view from the right end of Figure 1.

Figure 3 is a rear elevation.

It will be observed that the relation of the rectangular clock face within the border of the rectangular mirror is an important feature of the design, having ornamental lines on the glass of the mirror and bordering the clock face.

I claim:

The ornamental design for a mirror clock combination as shown and described.

STEPHEN C. COOK.
